James F. Splain
ATTORNEY.

UNITED STATES PATENT OFFICE.

EMIL R. SCHNITGER, OF WATERTOWN, WISCONSIN, ASSIGNOR OF ONE-HALF TO
CHARLES A. KADING, OF WATERTOWN, WISCONSIN.

STRAINER HOLDER.

Application filed April 2, 1928. Serial No. 266,859.

The object of my present invention is the provision of a simple, easily manipulated and efficient device for clamping and holding a strainer cloth on milk cans and the like.

5 To the attainment of the foregoing, the invention consists in the improvement as hereinafter described and definitely claimed.

In the accompanying drawings forming part of this specification.

10 Figure 1 is a plan view showing the preferred embodiment of my invention in use.

Figure 2 is a diametrical section of the same.

15 Similar numerals of reference designate corresponding parts in both views of the drawings.

The milk can 1 is of the conventional flared mouth type, and the strainer cloth 2 is also of ordinary well-known character.

20 My novel cloth holder and clamp is of general annular form. It comprises a plurality of sections 3 preferably of metal and each of which describes a part of a circle, retractile springs 4 interposed between the contiguous 25 ends of the sections 3, a continuous ring 5 also preferably of metal, and a circular series of spaced U-shaped arms 6 each with eyes 7 and 8 which receive a section 3 and the ring 5.

25 In the practical use of my improvement, 30 the strainer cloth 2 is positioned over the mouth of the can and draped over the can flange 9 as illustrated. The ring 5 is then placed over the cloth and immediately within the cloth portion adjacent to said flange 9, 35 after which the arms 6, sections 3 and springs 4 are moved from the positions shown by dotted lines to the positions shown by full lines in Figure 2, whereupon the springs 4 will be stretched and tensioned with the result

40 that the coacting sections 3 and springs 4 will tightly clasp and hold the cloth against the can flange 9 and at the same time will hold the ring 5 tightly in the position shown so that the cloth will be maintained in taut 45 state across the mouth of the can without

liability of the cloth becoming loose or being displaced. When, however, it is desired to remove the cloth from the can the same can

be readily accomplished after the arms 6, sections 3 and springs 4 are restored to the 50 positions shown by dotted lines.

In addition to the advantages thus far ascribed to my novel device it will be manifest that the device is very simple and strong and is susceptible of being easily and thoroughly 55 cleansed which is a desideratum in devices used for straining purposes.

Having described my invention, what I claim and desire to secure by Letters Patent, is:

1. A clamp or holder comprising a ring, 60 arms swingable about the ring, and an elastic annulus carried by the portions of the arms remote from the ring.

2. A clamp or holder comprising a ring, 65 arms swingable about the ring, and an elastic annulus carried by the portions of the arms remote from the ring; said arms being U-shaped to straddle the edge of a can mouth.

3. A clamp or holder comprising a ring, 70 arms swingable about the ring, and an elastic annulus carried by the portions of the arms remote from the ring; said elastic annulus including arcuate sections carried directly by the arms, and retractile springs 75 interposed between and connecting the contiguous ends of the sections.

4. A clamp or holder comprising a ring, 80 arms swingable about the ring, and an elastic annulus carried by the portions of the arms remote from the ring; said elastic annulus including arcuate sections carried directly by the arms, and retractile springs interposed between and connecting the contiguous 85 ends of the sections, and said arms being U-shaped and having end eyes receiving the ring and the arcuate sections.

5. A holder or clamp comprising means adapted to rest in a can mouth and an elastic annulus connected with the said means and 90 shiftable from a position within a can mouth-forming portion to a position about said portion.

In testimony whereof I affix my signature.

EMIL R. SCHNITGER.
